UNITED STATES PATENT OFFICE.

JOHN H. BALMER, OF MAPLEWOOD, NEW JERSEY.

DESIGN FOR A COMBINATION BATH FIXTURE.

Application filed February 23, 1928. Serial No. 25,553. Term of patent 14 years.

To all whom it may concern:

Be it known that I, JOHN H. BALMER, a citizen of the United States, and a resident of Maplewood, in the county of Essex and State of New Jersey, have invented a new, original, and ornamental Design for a Combination Bath Fixture, of which the following is a specification.

Reference is to be had to the accompanying drawing in which

Fig. 2 is a side elevation thereof.

What is claimed is—

The ornamental design for a combination bath fixture as shown.

Signed at Newark in the county of Essex and State of New Jersey this 17th day of February, A. D. 1928.

JOHN H. BALMER.
